Primary Examiner — Susan Moon Lee

(57) **CLAIM**

The ornamental design for a mobile computer device, as shown and described.

DESCRIPTION

FIG. 1 is a front perspective view of a mobile computer device;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

In drawing FIGS. 1-8, any broken lines and unshaded portions contained within broken lines, depict portions of the mobile computer device that form no part of the claimed design.

1 Claim, 7 Drawing Sheets
